(57) **CLAIM**

The ornamental design for a electronic keyboard instrument,
as shown and described.

DESCRIPTION

FIG. 1 is a perspective view of an electronic keyboard instrument showing my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a bottom plan view thereof.

Features shown with broken lines in the figures are intended
to show environmental structure only, and form no part of the
claimed design.
